CLAIM

The ornamental design for a positive airway pressure tube for sleep therapy, as shown and described.

DESCRIPTION

FIG. 1 is a perspective view showing my design;
 FIG. 2 is a front elevational view thereof;
 FIG. 3 is a rear elevational view thereof;
 FIG. 4 is a right side elevational view thereof;
 FIG. 5 is a left side elevational view thereof;
 FIG. 6 is a top plan view thereof; and,
 FIG. 7 is a bottom plan view thereof.
 The portions of the positive airway pressure tube for sleep therapy shown in broken lines form no part of the claimed design.
